203,554

COMBINED SLICER AND DISPENSER FOR BUTTER OR THE LIKE

David J. Jacoby, 1268 Fleetwood Road, Rydal, Pa.

Filed Jan. 25, 1965, Ser. No. 83,562

Term of patent 14 years

(Cl. D52—2)

I claim:

The ornamental design for a combined slicer and dispenser for butter or the like, as shown and described.
